UNITED STATES PATENT OFFICE.

JOHN L. CONROY AND JOSEPH SHIMON, OF POCOHONTAS, IOWA.

DITCHING-MACHINE.

1,183,633.

Specification of Letters Patent.

Patented May 16, 1916.

Application filed May 6, 1914. Serial No. 836,659.

To all whom it may concern:

Be it known that we, JOHN L. CONROY and JOSEPH SHIMON, both citizens of the United States, and residents of Pocahontas, 5 in the county of Pocahontas and State of Iowa, have invented certain new and useful Improvements in Ditching-Machines, of which the following is a specification.

Our invention relates to ditching machines of the tractor type, our more particular purpose being to provide a device of this character having an excavating wheel, driven from the source of power used for propelling the machine along.

15 More particularly stated, we seek to improve the efficiency of the machine by arranging for its complete control by the operator, and especially with reference to the changing of the position of the excavating

20 wheel while the machine is in action.

As is well understood in this art, a ditching machine, if of considerable power, presents many difficulties with regard to the weight of the various movable parts of the 25 machine.

What we seek to do is to enable the operator to raise or lower the excavating wheel to any desired extent within reasonable limits, and to maintain the excavating 30 wheel at the proximate level to which it is thus shifted under control of the operator.

We further seek to provide an improved form of cleaning wheel, to be used in connection with the excavating wheel, and practically automatic in its action.

Our invention further comprehends various improvements relative to the steering gear, the various other parts of the ditching machine, for the purpose of increasing the 40 general efficiency thereof.

Reference is made to the accompanying drawings forming a part of this specification, and in which like letters indicate like parts.

45 Figure 1 is a side elevation of the machine, certain parts being broken away. Fig. 2 is a side elevation of the machine, as seen from the opposite side from that appearing to the observer in Fig. 1. Fig. 3 is a fragmentary plan view of the ditching machine. Fig. 4 is a rear elevation of the same. Fig. 5 is a section, on the line 5—5 of Fig. 3, looking in the direction of the arrow. Fig. 6 is a section, on the line 6—6 of Fig. 1, looking 50 in the direction of the arrow, and showing

more particularly certain mechanism associated with the excavating wheel.

A U-frame is shown at 7 and is movable 60 relatively to the side bars 8, 9, the latter forming a part of the general frame work of the machine. A floor is shown at 10 and has the form of a platform upon which the operator stands. The front wheels appear at 11 and are mounted upon stub axles 12, the latter being journaled in bearings 13. 65 The stub axles are provided with sprocket wheels 14 mounted rigidly thereupon, and engaging these sprocket wheels are sprocket chains 15. These sprocket chains engage two sprocket wheels 16, the latter being 70 mounted rigidly upon the ends of a shaft 17 which extends practically the full width of the machine and is journaled in bearings 18.

Mounted rigidly upon the shaft 17 is a 75 sprocket wheel 19, and engaging the latter is a sprocket chain 20, this sprocket chain also engaging a sprocket wheel 21. The sprocket wheel last mentioned is supported upon the engine shaft which appears at 22. 80 The engine is shown at 23, and in this instance is an internal combustion engine. It is provided with a fly wheel 24 and with a clutch 25 for controlling the engine shaft 22.

A hand lever 26 is connected with the clutch 85 25 for throwing the same into and out of action. The rear wheels of the device are shown at 27 and are mounted upon stub shafts 28, the latter being controllable by bevel gears 29 which are revolubly supported upon bearing sleeves 30, the latter being connected rigidly with the framework, as may be understood from Fig. 4. Meshing with the bevel gears 29 are two other bevel gears 31, the latter being mounted rigidly 90 upon two shafts 32. These shafts carry two other bevel gears 33, and meshing with the latter is a bevel gear 34. A vertical shaft 35 is secured rigidly to the bevel gear 34, and mounted upon the top end of this vertical shaft is a hand wheel 36. The operator, by grasping this hand wheel and turning it, can, by transferring motion through the various gear members just mentioned, 95 shift the stub shafts 28 to different angles, 100 and thus move the rear wheels 27 into different angular positions relatively to the general frame work of the machine. The hand wheel 36 is thus a steering wheel, and the various parts intermediate this wheel 105

110

and the rear wheels 27, collectively constitute the steering gear. A bracket 37, provided with an upwardly extending post 37^a, constitutes a frame work for the gear wheels 33, 34 and the vertically extending shaft 35, as may be understood from Fig. 4.

Mounted upon the engine shaft 22 and controllable by a clutch 39 is a sprocket wheel 41. Connected with the clutch 39 for actuating the same is a hand lever 40. Journaled upon the engine shaft 22 are two links 42, 42^a. A link 43 is connected with the link 42 by a shaft 43^a. This shaft also connects the link 42^a with a link 44, which is substantially parallel to the link 43. Mounted upon the shaft 43^a are two sprocket wheels 45, 46. A sprocket chain 47 engages the sprocket wheels 41 and 46. A sprocket chain 48 engages the sprocket wheel 45 and also a sprocket wheel 49.

Mounted rigidly upon a shaft 44^a (see Fig. 5) is a gear pinion 50, located within a housing 51, and thus protected. Engaging the gear pinion 50 is an annular rack 52, the teeth of which are disposed internally thereof. Encircling the rack 52 is a wheel rim 53, and mounted rigidly upon this wheel rim and disposed in the form of a circle are a number of spades 54. Supporting the wheel rim 53 are spokes 53^a carried by a hub 53^b. The parts just mentioned collectively constitute the excavating wheel. Extending through this hub is a sleeve 55, and mounted rigidly upon the latter is a belt pulley 56. A belt 57 engages this pulley, and also engages another pulley 58, the latter being rigidly mounted upon a revolvable shaft 59, which is supported above the U-frame 7 and practically carried thereby. A conveyer 60 is connected with the shaft 59 and actuated by movements of the same. A brace 61 is provided for the purpose of supporting this conveyer. Disposed adjacent the outer end of the conveyer is a spout 62 or chute, which is used for the purpose of discharging materials dropped upon it by action of the conveyer.

Mounted rigidly upon the frame work of the machine are three yokes 63, 64, 65 which extend upwardly, the yokes 63 and 64 being upon one side of the U-frame 7, and the yoke 65 being located upon the opposite side thereof. The yokes 63, 64, 65 are provided with vertically extending rack bars 66, 67, 68, and engaging these rack bars are three gear wheels 69, 70, 71. The gear wheels 69 and 71 are mounted rigidly upon a shaft 72 which extends the full width of the U-frame. A sprocket 73 is mounted rigidly upon the sleeve 55, constituting practically the shaft of the excavating wheel, as may be understood from Fig. 6. Engaging the sprocket wheel 73 is a sprocket chain 74 which also engages another sprocket wheel 75. The axle of the shaft upon which this sprocket

wheel 75 is mounted is shown at 76. Mounted upon the sleeve 55 is a clutch member 77, and mating this clutch member is another clutch member 78, which is provided with a hub 79, formed into a spool or reel, as may be understood from Fig. 6, and mounted upon the shaft 72. A cam thread 80, carried by the shaft 72, engages the hub 79 in such manner as to move the clutch member 78 longitudinally of the shaft 72 whenever the hub 79 is turned slightly in the proper direction. A cord 82 is wound partially around the hub 79, and is used for turning the latter relatively to the shaft 72, so as to force the clutch member 78 into engagement with the clutch member 77. The cord 82 is also wound upon a reel 83, the latter being of suitable form and proportions to be rotated by hand, by a person standing on the floor 10 by means of the crank handle 83^a on the shaft of the reel, the reel being locked in position by the ratchet wheel *a* and pawl *b*. Whenever this reel is turned so as to tighten the cord 82, the clutch member 78 is forced into engagement with the clutch member 77, which is always turning while the excavating wheel is being actuated. Whenever the clutch member 78 is thus brought into engagement with the clutch member 77, the shaft 72 is caused to rotate, and the gear wheels 69, 71 climb directly upward upon the rack bars 66 and 68. Motion being communicated from the sprocket wheel 73 through the sprocket chain 74, and sprocket wheel 75 to the shaft 76, the gear wheel 70 also climbs directly upward upon the rack bar 67. The U-frame 7 is thus raised directly upward, and yet all the while maintained parallel with the general upper surface of the frame work of the machine. As soon as the tension upon the cord 82 is slackened, the upward movement of the U-frame is stopped. Therefore, the operator, by skillfully handling the reel 83, may cause the U-frame 7 to assume and to be held at any desired level within the limits of its travel. If the reel 83 be so handled as to relax the cord 82, the U-frame drops downwardly by its own weight, owing to the disengagement with the clutch member 78 from the clutch member 77. The excavating wheel may, therefore, be adjusted to different levels relatively to the frame work of the machine, and this may be done even while the excavating wheel is in full action, and while the machine is traveling ahead. A post 84 carried by the floor 10, is used for supporting the hand reel 83. It is to be understood that the reel 83 may be provided with any suitable means for locking it in position after the excavating wheel has been adjusted.

Mounted rigidly upon the frame work of the machine is a pedestal 85, the general form of which may be seen in the upper portion of Fig. 2. This pedestal carries a bear-

ing 86 of a general cylindrical form, the axis of the bearing extending obliquely upward. Journaled within the bearing 86 is a dirt wheel 87 provided with outwardly extending pins 88, having roughly the form of spokes, and carrying dirt plates 89 at their outer ends. The dirt plates are of suitable form to pass loosely in between consecutive pairs of the spades 54, so that rotation of 5 the excavating wheel turns the dirt wheel, and the dirt plates 89 are thus automatically thrust in between the spades 54, as may be understood from Fig. 3. When, therefore, the machine is in action, and the excavating 10 wheel is turning, and cutting and carrying dirt, this dirt is pushed laterally out of the excavating wheel by action of the dirt wheel, and brought into engagement with the conveyer 60. Adjacent the excavating wheel 15 are a pair of guards 91 for protecting various parts of the mechanism from dirt falling from the excavating wheel. Located below the excavating wheel is a shovel point 92. Adjacent this shovel point and back of the 20 same is a shovel plate 93, which is mounted rigidly upon a bar 94, this bar being pivotally supported at its forward end on pivot 94'. The rear end of the bar 94 is connected with a rod 95, this rod carrying, adjacent its 25 upper end, a rack bar 96. This rack bar extends through a slot 97 in a plate 98, and is provided with a handle 99. The operator, by grasping the handle 99, may disengage the rack bar 96 from the plate 98, and may 30 then raise or lower the rack bar and secure it in a new position. In doing this, the operator gives different degrees of inclination 35 of the shovel plate 93. Two guards 100, each having the form of a disk, are disposed within the rim 53 of the excavating 40 wheel, and serve to protect parts within the latter from dirt.

The operation of our device is as follows: The parts being assembled and arranged as 45 above described and the engine 23 being in action, power is transmitted from the engine to the front wheels 11, and the machine thus travels ahead, after the manner of a vehicle. The excavating wheel, having been 50 placed at its proper level, suitable for the particular work in hand, the rotation of the excavating wheel causes it to dig and carry up dirt, which is located between the spades 54. By action of the dirt wheel 87 and 55 conveyer 60, the dirt, carried up by the excavating wheel, is removed and thrown off in a lateral direction, some distance from the machine.

The steering of the machine is accomplished, as above described, by aid of the steering wheel 36. The mechanism within the excavating wheel is protected against the action of dirt, by the disks 100. The 60 action of the conveyer depends upon the 65 action of the excavating wheel, and when the

excavating wheel slows down or stops, the conveyer does likewise.

We do not limit ourselves to the precise arrangement shown, as variations may be made therein without departing from the 70 spirit of our invention.

Having thus described our invention, what we claim as new and desire to secure by Letters Patent is as follows:

1. A ditching machine comprising an excavating wheel provided with a plurality of spades secured rigidly thereto and extending radially outward therefrom, a dirt wheel disposed adjacent said excavating wheel and inclined thereto, said wheels being provided with a plurality of spokes extending radially outward, and a plurality of dirt plates each mounted upon one of said spokes and so formed as to extend loosely in between consecutive pairs of said spades, and means for applying power to said excavating wheel. 75

2. In a ditching machine, the combination of a frame work, a U-frame carried by said frame work and movable relatively to the same, a plurality of yokes mounted upon said frame work, racks connected with said yokes and extending vertically therefrom, gear wheels journaled upon said U-frame and engaging said racks for the purpose 90 of raising and lowering said U-frame relatively to said frame work whenever said gear wheels are turned, supporting wheels for supporting said frame work, means for applying power to said supporting wheels in order to turn the latter and thus move said frame work and said U-frame, and mechanism for applying power momentarily to 95 said gear wheels in order to actuate the latter. 100

3. In a ditching machine, a frame-work provided with vertical and oppositely arranged racks, a vertically movable frame, a shaft mounted in the frame, pinions on the shaft meshing with the racks, an excavating 110 wheel loosely mounted on the shaft, means for operating the excavating wheel, a clutch connecting the excavating wheel with the shaft, and means for operating the clutch. 105

4. In a ditching machine, a frame-work provided with vertical and oppositely arranged racks, a vertically movable frame, a shaft mounted in the frame, pinions on the ends of the shaft and meshing with the racks, an excavating wheel loosely mounted 115 on the shaft, means for operating the excavating wheel, a clutch connecting the excavating wheel with the said shaft, one member of the clutch being carried by the wheel and the other mounted to turn and move 120 longitudinally of the shaft, and means for operating the said movable member of the clutch. 125

5. In a ditching machine, a frame-work provided with three vertical racks, two on 130

one side and one on the other side, a movable U-shaped frame, a shaft mounted in the forward part of the frame, pinions on the ends of the shaft and meshing with two of the 5 racks, a shaft mounted in the rear part of the frame and provided with a pinion meshing with the other rack, an excavating wheel loosely mounted on the first named shaft, means for operating the excavating 10 wheel, a clutch connecting the wheel with said shaft, means for operating the clutch, and means for operating the pinion of the second shaft from the excavating wheel.

6. In a ditching machine, a frame-work 15 provided with three vertical racks, two on one side and one on the other side, a movable frame, a shaft mounted in the forward part of the frame and provided with pinions meshing with two of the racks, a shaft 20 mounted in the rear of the frame and provided with a pinion meshing with the other rack, an excavating wheel having an elongated hub loosely mounted on the shaft, means for operating said wheel, a clutch 25 connecting the wheel with the shaft, means for operating the clutch, and gearing between the hub of the excavating wheel and the shaft carrying the single pinion.

7. In a ditching machine, a frame-work 30 provided with three vertical racks, two on one side and one on the other side, a movable frame, a shaft mounted in the forward part of the frame and provided with pinions meshing with two of the racks, a shaft 35 mounted in the rear of the frame and provided with a pinion meshing with the other rack, an excavating wheel loosely mounted on the first named shaft, means for operating the wheel, means for operating the shaft having a single pinion from the excavating 40 wheel, a clutch connecting the excavating wheel with the said shaft, one member of the clutch being carried by said wheel and the other member being mounted to turn on and move longitudinal of the shaft, the movable member carrying a spool, a reel at the rear of the frame, and a cable winding on said spool and reel.

In testimony whereof, we have signed our names to this specification each in the presence of two subscribing witnesses.
